UNITED STATES PATENT OFFICE.

VASILIOS SAKELAROPOULOS, OF NEW YORK, N. Y.

DESIGN FOR A FOLDABLE BOX OR CONTAINER.

Application filed December 30, 1922. Serial No. 4,769. Term of patent 7 years.

To all whom it may concern:

Be it known that I, VASILIOS SAKELAROPOULOS, a citizen of Greece, residing at New York, city, county, and State of New York, have invented a new, original, and ornamental Design for a Foldable Box or Container, of which the following is a specification, reference being had to the accompanying drawing, forming part hereof in which the figure illustrates in elevation the interior of a foldable box or container, showing my new design, the fabric with

which the interior is lined being decorated as shown.

I claim:—

The ornamental design for a foldable box or container, as shown.

Signed at New York city, N. Y., this 28 day of Dec., 1922.

VASILIOS SAKELAROPOULOS.

Witnesses:—

ANDREW X. ALEXAKIS,
MAURICE BLOCK.
